ADDRESS PLATE PRINTER

Edward J. Von Pein, Endicott, N. Y., assignor to
 American Business Machines Corporation, New
 York, N. Y., a corporation of New York

Application December 23, 1936, Serial No. 117,264

6 Claims. (Cl. 101—281)

This invention relates to printing machines of the kind using customers' tokens used as identification for charge accounts by and using said token for applying the customer's name and address on the sales slips of the salesman's man-
 5 fold book.

The main object of the invention is to provide an arrangement in a hand-operated printing machine of the above described character which
 10 avoids direct contact of the customer's token or address printing plate with the ink or imprinting medium whereby the token may be returned to the customer in unsoiled condition and the possibility of soiling the customer's hand or
 15 gloves may be avoided.

In the present embodiment of the invention the hand-operated printing machine co-operates with the sales slips to record on the latter in legible form data specific to the customer such as the
 20 customer's name and address. The printing machine includes; a token of a size and shape convenient to be carried by the customer and bearing in legibly embossed characters the desired sales data; a plurality of sales slips with inter-
 25 venting carbon sheets for effecting multiple printing; a device for readily associating the sales slips and tokens, and a manually-operated means for conveniently operating the printing instrumentalities to effect efficient and legible
 30 printing operations.

A still further object of the invention is to devise a simple means for carrying the inserted token and placing it in proper relationship with carbon paper coated on one side with carbon
 35 which is intimately associated with the underside of a sales slip so that direct contact between the carboned side and the address plate is prevented.

A still further object of the invention is to devise a carriage for carrying a plurality of sales
 40 slips and a means for manually reciprocating the carriage so that a rotating platen roller will effect the printing impression. The use of a single roller is advantageous since it permits even printing on all portions of the sales slips.

A still further object is to devise an operating connection between the carriage and the roller rotating means so that the roller is rotated by movement of the carriage as the carriage is moved for printing operations.

A still further object is to include an arrangement that moves the roller out of engagement with the sales slip after the printing impression is completed whereby the carriage may be re-
 45 turned idly. By such means only a single impression is made contrasting to prior art arrangements wherein a roller effects a double imprint, and very often adjacent imprints which affect the legibility of the printing impression.

A still further object is to provide an arrange-
 50

ment and construction of token that will permit the use of only certain tokens in a printing machine. As herein carried out projections stamped out from the address plate cooperate with special means in the machine of a store
 5 and unless there is a coincidence prevents its use in effecting the printing impression, thus to inform the salesman whether or not the customer has a charge account at the store where the token is presented.

The best embodiment of the invention at present known is illustrated in the accompanying drawings in which:

Fig. 1 is a plan view of the improved printing device, the casing having been removed. 15

Fig. 2 is a longitudinal sectional view taken on the line 2—2 of Fig. 1.

Fig. 3 is a longitudinal sectional view taken on the line 3—3 of Fig. 1.

Fig. 4 is a transverse sectional view taken on the line 4—4 of Fig. 1. 20

Fig. 5 is a plan view of the improved customer's token.

Fig. 6 is an end view of said token.

Fig. 7 is a side view of the carbon paper holder. 25

Sales slip carriage

The machine framework comprises a base plate 10 and integral side plates 11 and 12, (Fig. 4).

The sales slip carriage comprises a left side 30 rail 13 and a right side rail 14 and to the front ends of said rails there is attached an operating handle 15. At the opposite ends of the rails and beneath said rails there is secured a cross plate 16. The latter with the handle provide a rigid 35 framework for the slidable sales slip carriage.

To the bottom of the base plate 10 there is secured a pair of parallel bars 17 and 18 and the latter and the rails 13 and 14 are formed to receive and act as a retainer for a standard type-
 40 writer roller bearing 19. In this manner by handle 15 the sales slip carriage may be reciprocated in the framework.

Attached to the side rails 13 and 14 is a plate 20 which has an integral portion 21 bent upwardly and upon which sales slips to be addressed are placed. The integral portion 21 carries a pair of pins 22 which are received by perforations in the margin of the sales slips to properly locate them on the carriage. A bar 23 is attached 50 to the right end of the carriage and also carries a pin 24 for a similar purpose.

Attached to the plate 20 is a backing plate 25 for a customer's identification printing plate 26. 55 It will be seen that the top surface of the plate 21, the address printer plate 26 and the bar 23 are substantially in the same plane so that the sales slip is evenly located thereon for providing legible printing impressions.

60

Pressure roller

To the side rail 14 there is attached a bracket 27 (Fig. 1) carrying a pin 28 which is the pivot for a gear rack bar 29 provided with gear rack teeth 30 and at its underside with ratchet teeth 31 for a full stroke device. By means of parallel upward integral extensions 31 and 32 of the side plates 10 and 11 a rod 33 is carried and said rod is the pivot for a pair of bell cranks 34 which are tied together rearwardly by a rod 35 and at the forward arms by a shaft 36 to which is secured, a resilient impression roller 37, a gear 38, and at the end of the shaft a circular disk 39. As best shown in Fig. 2 the gear 38 meshes with the rack teeth 30 and a spring 40 connected between the rod 35 and a rod 41 carried by the side plates 31 and 32 maintains the meshing relationship during the rearward and forward movement of the carriage. To further insure such engagement the rack bar 29 is provided with a longitudinal rail 42 over which the circular disk 39 rolls. Depending from the shaft 36 is an arm 43 carrying a roller 44 which engages the bottom edge of the rail 42. In this manner the gear 38 and rack teeth 30 are kept in continuous mesh during the rearward and forward movement of the carriage.

Customer's identification printing plate and carbon paper holder

The carbon paper holder comprises a plate 45 provided with a rectangular aperture 46 and a pair of bent ears (Fig. 7) 47 through the holes of which passes a shaft 48 carried by the rails 13 and 14 to provide a pivot for the carbon paper holder.

As shown in Fig. 4 the plate 20 has an integral depending portion 49 which together with a spring plate 50 attached to the underside of the plate 20 pivotally carry a roll of carbon paper, the end of which passes around a curved guide portion 51 of the plate 45, over the aperture 46 of the plate 45 and between the forward edge of the plate 45 and a spring plate 52 (Figs. 1 and 7) which holds the end of the carbon paper against the plate 45 and functions as a tearing edge.

A rectangular spring wire bail 53 has its rear ends wound around the shaft 48 and so connected as to resiliently force the spring wire bail against the under surface of the plate 45 so that when the carbon paper holder is manually rocked the spring wire bail will move with it, although the plate 45 and spring wire bail may be relatively separated for the interposition of a printing plate as will be later explained.

Customer's identification printing plate

Referring to Figs. 5 and 6 reference character 54 designates an address printing plate having raised printing characters 55 in reversed order and which characters are formed in a raised portion 56 of the plate 54. A border 57 is formed on the four sides of the raised portion 56. The indentations in the under surface of the raised portion formed by the raised type are preferably filled in white so that the name and address are easily readable. The flanged border carries a pair of pins 58 which vary in number and location so that only certain address printing plates can be used in printing machines of certain stores.

Operation

The carbon paper holder is first rocked about its pivot 48 and the address printing plate from which printing is to be effected is inserted between the spring wire bail 53 and the bottom of the plate 45 and if the carbon plate holder is rocked sufficiently the back of the address printing plate is in view to permit reading of the characters. The address printing plate can be placed in the desired position to register with the blank portion of the sales slips to be printed. In Fig. 1 it is shown in the extreme rearward position. The carbon paper holder is then restored to its lower position with the carbonized face of the carbon paper upward, or in other words, the plain face of the carbon paper is in contact with the raised printing type.

A book of one or more sales slips with carbons interleaved with the sales slips is placed upon the carriage with their holes receiving the pins 22 and 24. The underside of the bottom slip will be in immediate contact with the carbonized face of the carbon paper, and each interposed carbon has its carbonized face in immediate contact with the underside of the sales slip just above it, so that for each sales slip to be printed upon the printing will be effected underneath. For this reason the book of sales slips is placed on the carriage with the printed face down.

The handle 15 is then grasped and the carriage with the soles slips are moved rearwardly and the rack bar 29 will rotate the gear 38 and turn the printing roller 37 which being under pressure by the spring 40 presses each sales slip down against the adjacent carbon and all against the raised printing type. The resiliency of the platen and the raised printing type will effect a printing impression on the under surface of each sales slip.

Coacting with the ratchet teeth 31 is a spring-urged pawl 60 pivoted on the side plate 12 which 40 engages the successive teeth of the rack bar 29 as the carriage is moved rearwardly preventing the carriage from being drawn back until the carriage is moved rearwardly a full stroke.

When the carriage is pushed all the way back 45 a pair of inclined portions 61 (Figs. 1 and 7) of the plate 45 coacts with the periphery of the roller 37 causing the frame carrying the roller to rock about pivot 33 and in so doing a half-flattened stud 62 (Fig. 2) carried by one of the 50 bell cranks 34 will be elevated. A spring 63 connected to a latch arm 64 will thereupon rock the latter so as to engage the stud 62 thus holding the roller carrying frame in rocked position and above the upper surface of the top sales slip.

An extension 65 of the latch arm 64 coacts with a lug 66 of an extension of the pawl 60 and when the latch arm is rocked it rocks the pawl 60 so as to disengage it from the ratchet teeth 31 to permit the sales slip carriage to be restored forwardly, and with the printing roller 37 out of coaction with the upper surface of the top sales slip during such restoration so as to prevent overprinting.

When the carriage approaches its normal position as it is drawn forwardly a pin 67 carried by the rack bar 29 will engage the pawl 60 rocking it counterclockwise so that its lug 66 will rock the latch arm 64 clockwise disengaging it from the stud 62 and permitting spring 40 to rock the platen roller carrying the frame to normal position. The pawl 60 is now in position to engage the ratchet teeth 31 to cause a full stroke of the sales slip carriage during its succeeding rearward movement.

Selective means to permit printing from predetermined printing plates

Formed in the carbon paper holder plate 45 is a series of holes 69 which coincide with the pins 58 of the printing plates which are adapted to be used in connection with a certain machine. When all the pins 58 register with the holes on each side of the plate 45 the raised printing characters will project from the upper surface of the plate 45 so as to be contacted by the periphery of the roller 31.

However, upon the insertion of a printing plate having pins 58 which do not register with the holes of the plate 45 it will be seen that when the carbon plate holder is rocked to printing position, the side of the plate 45 not having a hole to register with a pin of the plate 45 will not properly seat on the plate 20 so that either side or flange of the plate 45 will be retained elevated causing the printing roller 31 to be immediately rocked upward to latched position when the carriage is initially moved rearwardly. In this manner a printing impression from undesired printing plates is prevented.

The normal restoration of the sales slip carriage will unlatch the printing roller as previously described. It can also be effected by manually rocking the latch arm 64 by a stud 70 attached thereto, and shown in Figs. 1, 2 and 4. The absence of an imprint in the sales slips will indicate to the operator that an improper printing plate has been employed.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is as follows:

1. A machine for printing sales data specific to a customer on a sales slip comprising, a manually reciprocable carriage, means carried by said carriage for carrying an inking medium and detachably holding a printing plate and a sales slip to be imprinted which are manually positioned thereon, means for effecting a printing impression from said printing plate comprising a rotatable platen roller normally out of operative relation with said carriage to enable a free manual positioning of the sales slip and printing plate thereon, a driving means for said platen roller comprising means carried by the carriage and operated by the manual movement of said carriage for rotating said platen roller as said platen roller presses the sales slip and inking medium against type carriers of said printing plate, a frame carrying said platen roller, and means rendered effective by said carriage at the extremity of its movement for effecting the printing impression for holding said frame in elevated position to retain the platen roller out of cooperative relation with said sales slip during the return movement of said carriage.

2. A machine according to claim 1 in which said driving means comprises a driving rack carried by the carriage meshing with a gear rotatable with said platen roller, and said means for holding and retaining the platen roller elevated

comprises a latching means for said frame, and means carried by said carriage for rendering the latching means effective at the extremity of the movement of said carriage in one direction and ineffective at the extremity of the movement of the carriage in the other direction.

3. A machine according to claim 1 in which said inking medium comprises a sheet of carbon drawn from a supply roll, and the means for carrying the inking medium comprises, an apertured plate pivoted in said carriage over which the carbon strip is positioned to cause the carbon sheet to be interposed between the sales slip and the printing plate registering with the aperture, said carbon sheet having its carboned surface in intimate contact with the undersurface of the sales slip whereby the printing plate is free of any contact with the ink.

4. A machine for selectively printing identification data from a printing plate provided with identification control means comprising, a manually movable carriage carrying; a sales slip, an inking means and said printing plate, a platen roller normally out of cooperative relation with the carriage for pressing the sales slip against said inking medium and printing plate by the movement of said carriage, a base plate of said carriage on which a plate to be used with the machine and printed therefrom rests, a plate holder carried by said carriage and provided with means interfitting with identification control means carried by the printing plate to enable the plate holder to properly hold the printing plate on the base plate when there is an interfitting of cooperative parts of the plate holder and printing plate, whereby said platen roller may effect a printing impression from said printing plate on the sales slip.

5. A machine according to claim 4 in which said plate holder is pivoted in said carriage and is provided with control apertures receiving identification control pins carried by the printing plates to be used with the machine, the absence of an interfitting condition causing said plate holder to be elevated above a normal position, means for supporting said platen roller, and means comprising part of said holder for causing at the start of the manual movement of the carriage when said plate holder is elevated above normal the elevation of said supporting means to prevent the platen roller from contacting with said sales slip whereby a printing impression from a printing plate not adapted to be used with the machine is prevented.

6. A machine according to claim 4 in which said inking medium comprises a carbon sheet carried by said printing plate holder and provided with control apertures receiving identification control pins carried by the printing plates to be used with the machine, said plate and inking medium holder being adapted to be retained elevated above its normal position in the absence of interfitting parts of the plate and holder, a frame carrying said platen roller, and means comprising part of said holder for causing at the start of the manual movement of said carriage when said holder is elevated above its normal position the elevation of said frame to prevent the platen roller from contacting with said sales slip whereby a printing impression from a printing plate not adapted to be used with the machine is prevented.

EDWARD J. VON PEIN.

Patent No. 2,161,602.

CERTIFICATE OF CORRECTION.

June 6, 1939.

EDWARD J. VON PEIN.

It is hereby certified that the name of the assignee in the above numbered patent was erroneously described and specified as "American Business Machines Corporation" whereas said name should have been described and specified as International Business Machines Corporation, of New York, N. Y., a corporation of New York, as shown by the record of assignments in this office; and that the said Letters Patent should be read with this correction therein that the same may conform to the record of the case in the Patent Office.

Signed and sealed this 25th day of July, A. D. 1939.

(Seal)

Henry Van Arsdale,
Acting Commissioner of Patents.
